UNITED STATES PATENT OFFICE

2,604,164

TRIMMING AND PUNCHING MACHINE FOR
FORGED BLANKS

Jacob Gavurin, Brooklyn, N. Y.

Application June 19, 1949, Serial No. 98,180

6 Claims. (Cl. 164—13)

1

This invention relates to a machine for trimming and punching forged blanks and relates more particularly to an automatic machine arranged for continuous operation and having novel feeding means for receiving the blanks and delivering them to the punching and trimming station, trimming the flash from the blank while simultaneously punching any openings in the blank, delivering the finished blank to one chute or receptacle and delivering the flash to another.

The machine of the present invention is effective for trimming forged blanks of a wide variety and which have been formed by any die rolling or drop forging operation. It is most useful, however, in connection with the roller forging machine which is disclosed in my co-pending application Serial No. 95,309, filed May 25, 1949. This machine employs driving means which may be conveniently used for driving the trimming and punching machine of the present invention and the latter may be placed in close juxtaposition to said forging machine and receive the blanks directly as they are forged for operation on by the instant machine.

In some instances, however, it may be desirable to heat the stock before the forging operation and permit cooling before the trimming operation. For this purpose the present machine is also provided with a conveyor provided with fingers which grasp the forged blanks, conveys them for a sufficient period of time to effect cooling and then delivers them to the primary feeding means of the trimming machine.

Thus, an important object of the present invention, in its complete aspect, is to provide an automatic machine capable of continuous operation which receives the untreated stock and delivers the finished blank, ready for further operations, such as machining, drilling, grinding and polishing, if such is necessary.

A further object of the invention is to provide a punching assembly having improved means for accurately positioning the forged blank relative to the trimming dies and for facilitating removal of the finished blank and the waste which has been trimmed from the blank.

In accordance with the present invention, the rolled, hot blank is grasped by fingers mounted in spaced relation on the conveyor belt which traverses a tortuous path of considerable length although the overall dimensions of the entire assembly are relatively small. The cooled blank is then delivered to a novel feeding assembly formed with inwardly movable, cam-operated fingers which move the blank to the trimming and

5
5
10
15

punching station and accurately deposit it on a female die at which instant a male die descends and trims the flash from the blank while at the same time straightening any deformities in the blank.

A yieldable plunger within the female die recedes as the male die descends and there is sufficient resistance to the yielding movement to bring about a straightening of the blank, should 10 there be any deformation therein during the rolling operation, by the compressive action between the male die and the plunger. The flash which is now freed from the trimmed blank is now picked up and delivered to one chute while the blank is delivered to another chute.

In the drawings:
Fig. 1 is a plan view of a trimming and punching machine embodying the present invention with the punch press assembly for the upper or 20 male die removed.

Fig. 2 is a side elevation thereof partially in section, the part in section being taken on line 2—2 of Fig. 1.

Fig. 3 is a broken section taken on line 3—3 25 of Fig. 1.

Fig. 4 is a transverse section taken on line 4—4 of Fig. 3.

Fig. 5 is a broken section taken on line 5—5 of Fig. 3.

Fig. 6 is a broken side elevation of the conveyor 30 for the trimmed blank.

Fig. 7 is similar to Fig. 6 but shows the parts in a different position.

Fig. 8 is a broken side elevation of the conveyor for the flash.

Fig. 9 is similar to Fig. 8 but shows the parts in a different position.

Fig. 10 is a broken section taken through a part 35 of the machine.

Fig. 11 is another broken section taken through a part of the machine.

Fig. 12 is a broken perspective view of the feeding mechanism.

Fig. 13 is similar to Fig. 12 but shows the parts in a different operating position.

Fig. 14 is a side elevation of the conveyor 40 comprising the blank cooling means.

Fig. 15 is a plan view partly in section of the blank gripping unit in open position.

Fig. 16 is similar to Fig. 15 but shows the blank 45 gripping unit in closed position.

The feeding means for the rolled blanks are operated by two spaced reciprocating rods 10 and 11 which are driven by any suitable means such as that shown in my copending application pre-

viously referred to. These rods correspond to rods 114 and 115 illustrated in such application.

If the rolling operation is done while the metal is cold or if there is no particular reason for cooling the rolled blanks before they are punched and trimmed they are fed along frame member 12 where they are picked up by reciprocating jaw members 13 and 14 which are mounted on slides 15 and 16 by means of a pin and a slot connection 17 which permits adjustment of the jaw members relative to their supporting slides. The slides have tracks 21 which are received in trackways 22 in blocks 23 and 24. These blocks have tracks 25 which are received in trackways 26 in fixed frame members 30 and 31. A cam member 32 is pivoted at 33 on each block and inward movement of each slide 15-16 is produced by a diagonal cam portion 34 which engages a diagonal edge 35 of an extension 36 of the slide.

Blocks 23 and 24 are connected with driving rods 10 and 11 respectively, as shown at 40. As the rods and the blocks move rearwardly to starting position the lower ends of cams 32 contact fixed stops 41 and rotate the cams in a counter-clockwise direction (Fig. 12), thus moving the slides and the jaw members carried thereby inwardly to pick up the formed blank and as the rods move forwardly on the beginning of the next cycle the jaws move forwardly and are retained in their inward position by virtue of the upper ends of cams 32 contacting the outer surfaces of extensions 34. They retain this position until the blocks move forwardly to a point wherein cams 32 contact cam lifters 42 at which time the slides and the jaw members are released for outward travel which may be accomplished by springs (not shown).

Cam lifters are carried on a cross piece 43 which is moved to an adjusted fixed position by means of a lead screw 44 journaled in frame members 45 and 48.

The cutting and trimming assembly embodies a punch press arrangement which is driven by means of a crank shaft 46 journaled in upright frame members 47 and 51. Any suitable driving means may be employed for turning this shaft such as cranks 52 to which are connected driving rods 53 which may be connected with a gear 54 keyed to one of the shafts 55 of the rolling assembly 56 which forms the subject matter of my co-pending application.

A central crank portion 60 supports a shaft 61 which is received in bearings 62 carried at the upper end of a plunger 63. As shaft 46 rotates, plunger 63 reciprocates and produces vertical reciprocating movement in a punching assembly 64 which includes a plate 65 carrying a shaft 66 disposed in an opening 67. The lower end of the plunger is provided with a collar 70 which is mounted on the shaft.

The punching assembly further includes a lower plate 71 secured in spaced relation with the upper plate by means of side plates 72. The assembly is mounted for vertical reciprocating movement in trackways 73. On the lower surface of plate 71 a recess 74 is formed which receives the male or punching die 75 shaped in accordance with the outer contour of the finished blank. To free the die from the work after the trimming operation a depressible plate 76 mounted on pins 77 is urged downwardly by springs 81.

An intermediate plate 82 is mounted for reciprocating movement on pins 83 and is urged upwardly by springs 84. This plate carries a punch 85 for punching out any central portion

of the blank and is moved downwardly independently of the die 75 by a projection 86 of collar 70 which engages a raised portion 90 on plate 82. The punch passes through an opening in male die 75. Plunger 63 has a rocking action at its upper end and when it moves to the vertical position of Fig. 3 projection 86 has moved plate 82 carrying plunger 85 downwardly.

The female die 91 has an opening 92 shaped complementary to the male die and a plunger 93 therein which moves the finished blank 97 out of the recess at the end of the operation. The plunger is mounted on a plate 94 which is supported by pins 95 which are mounted for vertical reciprocating movement in frame members 96.

This plate is urged upwardly by springs 100 but in order to make the upward travel more positive links 101 are pivoted on the lower surface of the plunger which in turn is connected with one arm 102 of a bell-crank lever centrally pivoted at 103. The other end 104 of the bell-crank lever is engaged by the terminals of a driving member 105 mounted for rotation on shaft 106.

The rolled blank which includes the flash which must be trimmed by the trimming die assembly is moved to trimming position by jaw members 13-14 just described and the male die descends for the trimming operation. As the male die ascends the plunger moves the blank upwardly out of recess 92. The upper surface of the plunger is now plane with the upper surface of the female die. Separate means are now provided for moving the finished blank forwardly to deposit it in a chute 110 and for moving the flash 98 forwardly to deposit it in a second chute 111. The first means comprise an arcuate finger 112 carried on a shaft 113 which is rigidly mounted on an angle bracket 114.

This bracket is adjustably secured by means of a pin and slot connection 115 with a second bracket 116 which is pivoted at one end 117 to a plate 121. This plate is suitably secured to block 23 and is arranged to travel with it. After the trimming operation the block moves forwardly, bringing with it the new blank for trimming and punching and this travel also advances finger 112 which moves the finished blank to chute 110. The finger glides over the top of the female die 91 due to gravity. At the end of the stroke it must be raised for the return travel so as to avoid displacing the new blank about to be trimmed. This is accomplished by the arrangement shown in Figs. 6 and 7. The opposite end of bracket 116 carries a laterally extending pin 122 which underlies a plate 123 secured to the frame 125 by a pin and slot mounting 124. At the end of its forward stroke, pin 122 contacts an inclined surface 126 of a spring urged camming member 130 mounted in a socket 131. This slightly raises the pin and on the return stroke it rides up an inclined surface 132 of plate 123. At the end of the return stroke the pin has passed the inner end 119 of plate 123 and the bracket falls to starting position.

The means for conveying the flash or trimming to chute 111 is shown in Figs. 8 to 11. An assembly 133 includes a support 134 having a track 135 mounted in trackaway 127 (Fig. 4). This support is connected with the rod 11 and second block 24 by a rod 138 and bracket 139 and is arranged to travel therewith. It is further supported for reciprocating travel by a track 136 mounted in a trackway 137 in frame member 140. The assembly includes an upper finger 141 which

is fixed, and a lower finger 142 which is arranged to move toward the fixed finger to grasp the trimming for delivery to chute 111. Spaced set screws 143 (Fig. 11) permit the flash to be grasped on opposite sides of the opening formed by separating the flash from the trimmed blank. The lower or movable finger 142 is pivoted at 144 and a pivoted link 145 carried at its opposite end is provided with a pin 146 at its lower end. Thus, as the pin moves down, against the action of compression spring 153, the grasping end of the finger 142 moves up and grasps the flash.

Means for moving pin 146 downwardly comprise an elongated cam plate 150 carried by a vertical supporting plate 151 which is mounted for limited vertical movement in the frame 140. A supplemental frame member 152 acts as a track to retain plate 151 in sliding engagement with frame 140. Supporting plate 151 is urged upwardly by springs 153 inclined forward terminal portion 154 and a downwardly inclined rear terminal portion 155. On its forward travel (Fig. 8) pin 146 rides on the lower surface of cam plate 150, thus raising the pivoted flash-grasping finger 142 and moving the flash forwardly to chute 111. As it reaches its forward end of travel, the pin is moved upwardly by spring 150 and it rides up cam surface 154 thus forcing cam plate 150 and its support downwardly to the position of Fig. 9. Thus, on its rearward travel the pin rides the upper surface of the cam plate and when it passes the rear terminal, the plates moves back to the position of Fig. 8, due to the action of springs 153 and on its next forward travel it moves down cam surface 155 to the position of Fig. 8.

In its rearward travel the supporting element 151 for cam plate 150 is retained in its lowered position by means of a hinged finger 160 to prevent binding. On its forward travel the finger is moved by friction in a counterclockwise direction (Fig. 8), thus releasing the support for upward movement.

In the event that the stock is not heated prior to the rolling operation which is performed by the machine of my co-pending application or if the work is of such character as to have a relatively thin flash and no cooling is required, the fingers 13-14 pick up the rolled blank in the manner earlier described and operate upon it.

If cooling is required, the conveyor means shown in Figs. 14 and 15 are employed. The conveyor assembly is so positioned relative to the rolling assembly as to successively pick up each rolled blank with the flashing yet intact, convey it in a tortuous path of such length as to effect sufficient cooling, and then deliver it to the fingers 13-14 which feed it to the punching and trimming means earlier described.

Fig. 14 shows the whole arrangement schematically and certain details of the conveyor assembly as well. So far as the die rolling machine is concerned, this figure shows a frame 165 which provides journal bearings for upper and lower die rolling members 166 and 167 which are suitably driven by means which are not shown. A gear 172 is also driven by the gears associated with the die rolling members and a crank 173 secured radially of such gear is connected at its outer end to a rod 174 which imparts reciprocating motion to a work feeding member 175. A heater 176 heats the stock before it is engaged by the dies. The rolled blank is fed to a platform 177. All of the foregoing structure forms the subject matter of my co-pending application earlier referred to. Fig. 14 further shows the

driving rod 53 connected with the upper die assembly for driving shaft 46.

The conveyor assembly includes vertical frame members 181, 182, 183 and 184 which provide bearings for rollers 185 which support an endless conveyor belt 186. The member 186 may be a belt or a chain and in Figs. 15 and 16 is shown as two spaced chains 187 and 188. The blank gripping members which are mounted in spaced relation on the belt are designated generally by the numeral 189 in Fig. 14 and the details thereof are shown in Figs. 15 and 16.

Each such unit comprises plates 193 and 194 having flanges 195 which are secured to the chains by the headed pins 196 forming the pivots for the links of the chains. A bell crank lever is pivoted on each plate at 200 and one leg 201 thereof is provided with a roller 202 which engages a fixed cam member 203 to close the assembly and a cam member 204 to open the same. The opposite leg 205 is connected with a pivoted link 206, the inner end of which is connected with a slide 207 mounted for movement transversely of its supporting plate.

Suitable detent means for holding the bell crank lever in the open or closed position may comprise a spring pressed pin 210 which engages one or the other of two spaced notches 211.

In operation, the rolled blanks are fed over frame 177 where they are picked up by units 189 which are caused to move to closed position by the rollers on the bell crank lever contacting cams 203. The belt is of suitable length as to effect cooling of the blanks at which time the units open upon contact with cams 204 at which time they are picked up by fingers 13-14 and are fed to the punching and trimming station.

The male die descends along with the punch and the flashing is picked up by fingers 141-142 which deliver it to chute 111. Simultaneously, pivoted finger 112 moves the finished blank to chute 110 and the operation is complete. A driving gear not shown is arranged for continuous rotation and while it is not shown, it may be said to effect a complete operation of the entire machine with each revolution thereof. Utilizing a single blank, four revolutions or cycles are required to process the said blank from the raw material into a finished product. In the first cycle, the blank portion of a piece of stock fed to the forming jaws, formed and the jaws retracted. The second cycle feeds the formed blank into engagement with the rollers, severs the blank from the stock, rolls and ejects the said blank.

The above operations are the subject matter of my cited co-pending application. Briefly, the feed assembly 175 reciprocates to effect feeding under control of gear 172. With each complete rotation thereof, assembly 175 moves forwardly for 180° of the cycle and rearwardly during the remaining 180°. The forming jaws, not shown, are controlled by the assembly 175 and are effective at approximately 150° of the forward stroke and release at 210° of the cycle. The first 150° feeds the stock to the forming jaws. During the second cycle the feeding operation is repeated, however the formed or bent stock is moved into engagement with the rollers 166, 167, rolled and severed into a blank and stripped from the rollers within the first 150° of the second cycle. The remainder of the cycle merely returns the rolling dies to normal. At approximately 350° of the second cycle the jaws 13, 14 are moved into engagement with the rolled blank. On the succeeding, or third cycle the closed jaws 13, 14 move forwardly for

180° thereof. However, at approximately 140° of the cycle the jaws 13, 14 release the blank on the die 91 and expand outwardly in time to clear the now descending trimming male die which is effective from 140° to 200° of the cycle. As the jaws 13, 14 return, the plunger has ascended sufficiently to permit the passage thereof. The remainder of the cycle is utilized in returning the parts to normal. Rods 10 and 11 reciprocate concurrently with the feed assembly 175 therefore jaws 13, 14 feed in time therewith. Finger 112 and the coacting fingers 141, 142 move the blank and the flash, respectively during the initial 180° of the cycle, at which time they are deposited in appropriate chutes 118, 111. During the latter 15 180° of the cycle, the said fingers return to normal in preparation for the next cycle.

It is understood however that the above process is continuously repeated and every cycle a finished article is produced.

Where cooling is desired between the rolling and trimming operations, the units 189 are arranged to grasp the rolled blank on the platform 177 where it was deposited during the second cycle. Where the jaws 13, 14 previously engaged the blank, the units 189 now perform the same function during the first part of the third cycle. The time is not critical at this part, there being approximately 210° of the third cycle remaining. However, the releasing of the now cooled blank by the units 189 is arranged to occur just prior to the closing of the jaws 13, 14. This timing arrangement is accomplished by predetermining the length of the conveyor belt and by planned spacing of the units 189.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from its principles thereof.

I claim:

1. A trimming machine for forged blanks comprising a frame, a block mounted for longitudinal travel on the frame and provided with inwardly movable fingers which grasp and feed the forged blanks to the trimming and punching station, a male trimming die slidably supported in the frame for downward movement, a fixed female die having an opening corresponding to the contour of the male die and a yieldable plunger therein arranged to move the blank out of the female die, positive drive means for raising said plunger, chutes for the blank and the flash, a blank delivering finger pivotally mounted on the block for moving the blank to one chute, cam means for raising the finger for the return movement and a flash-gripping assembly comprising fixed and movable fingers mounted on the block for delivering the flash to another chute.

2. A trimming and punching machine for forged blanks comprising a frame, a blank feeding assembly mounted for longitudinal travel on the frame and provided with inwardly movable fingers which grasp the forged blank and deliver it to a trimming and punching station, a male trimming die slidably supported in the frame for downward movement, a punching die carried by the trimming die, a fixed female die having an opening corresponding to the contour of the male die and a yieldable plunger therein arranged to move the blank out of the female die, a blank delivering finger pivotally mounted on the block for moving the trimmed blank from said station, an elongated cam for raising the finger for the return movement, a flash-gripping assembly comprising fixed and movable fingers mounted on the block for moving the flash away from said station, and means for moving the movable finger toward the fixed finger during forward travel of the block and releasing it during rearward travel thereof.

opening corresponding to the contour of the male die and a yieldable plunger therein arranged to move the blank out of the female die, a blank delivering finger pivotally mounted on the blank feeding assembly for delivering the trimmed blank, an elongated cam for raising the finger during return movement, a flash-gripping assembly comprising fingers mounted on the conveyor assembly for delivering the flash after the trimming operation.

3. A trimming machine of the character described and comprising a frame, a blank feeding assembly mounted for longitudinal travel on the frame and provided with inwardly movable fingers which grasp and feed a forged blank to the trimming and punching station, a male trimming die slidably supported in the frame for downward movement, a fixed female die having an opening corresponding to the contour of the male die and a yieldable plunger therein arranged to move the blank out of the female die, chutes for the blank and the flash, blank delivering means pivotally mounted on the conveyor assembly for moving the blank to one chute, a flash-gripping assembly comprising fingers mounted on the blank feeding assembly for delivering the flash to another chute, one of said fingers being movable and another being fixed and means for moving the movable finger toward the fixed finger during forward travel of the conveyor assembly and releasing it during rearward travel thereof.

4. A trimming and punching machine for forged blanks comprising a frame, a block mounted for longitudinal travel on the frame and provided with inwardly movable fingers which grasp and feed the forged blanks to the trimming and punching station, a male trimming die slidably supported in the frame for downward movement, a punching die carried by the trimming die, a fixed female die having an opening corresponding to the contour of the male die and a yieldable plunger therein arranged to move the blank out of the female die, chutes for the blank and for the flash, a blank delivering finger pivotally mounted on the block for moving the blank to one chute, an elongated cam for raising the finger during the return movement, a flash-gripping assembly comprising fixed and movable fingers mounted on the block for delivering the flash to another chute, and means for moving the movable finger toward the fixed finger during forward travel of the block and releasing its grip during rearward travel thereof.

5. A trimming and punching machine for forged blanks comprising a frame, a block mounted for longitudinal travel on the frame and provided with inwardly movable fingers which grasp and feed the forged blanks to the trimming and punching station, a male trimming die slidably supported in the frame for downward movement, a punching die associated with the trimming die, a fixed female die having an opening corresponding to the contour of the male die and a yieldable plunger therein arranged to move the blank out of the female die, a blank delivering finger pivotally mounted on the block for moving the trimmed blank from said station, an elongated cam for raising the finger for the return movement, a flash-gripping assembly comprising fixed and movable fingers mounted on the block for moving the flash away from said station, and means for moving the movable finger toward the fixed finger during forward travel of the block and releasing it during rearward travel thereof.

and comprising an elongated floating cam, mounted in the frame, a pin carried by the finger which engages one edge of the cam during forward travel and another edge of the cam during rearward travel.

6. A machine for trimming forgings and comprising a frame, means for feeding the forged blanks to the trimming assembly, fixed and movable trimming dies which operate on the blank, a blank delivering finger pivotally mounted on the feeding means for moving the trimmed blank from the dies, an elongated cam for raising the finger for the return movement, a flash-gripping assembly comprising fixed and movable fingers mounted on the feeding means for moving the flash away from said station, and means for moving the movable finger toward the fixed finger

during forward travel of the feeding means and releasing it during rearward travel thereof and comprising an elongated cam mounted in the frame, a pin carried by the finger which engages one edge of the cam during forward travel and another edge of the cam during rearward travel.
